US00D597161S

(12) United States Design Patent
Blair et al.

(10) Patent No.: US D597,161 S
(45) Date of Patent: * Jul. 28, 2009

(54) BILLIARD TABLE CORNER POCKET
COMPONENT

(75) Inventors: Jesse Nicholas Stanford Blair,
Whitefish Bay, WI (US); Adam W. Callif, Chicago, IL (US); Joseph M. MacCarthy, Oakland, CA (US); John Zebley, Saratoga Springs, UT (US)

(73) Assignee: Brunswick Bowling & Billiards Corporation, Lake Forest, IL (US)

() Term: 14 Years

(21) Appl. No.: 29/292,168

(22) Filed: Sep. 26, 2007

(51) LOC (9) Cl. 06-06

(52) U.S. Cl. D21/783

(58) Field of Classification Search D21/782-784;
D6/329, 360, 491-496, 422, 423, 428; 473/1,

(57) CLAIM

The ornamental design for a billiard table corner pocket component, as shown and described.

DESCRIPTION

FIG. 1 is a perspective view of a billiard table corner pocket component of our new design.

FIG. 2 is a top view thereof; and,

FIG. 3 is a side view thereof.

The broken lines showing environment are for illustrative purpose only and form no part of the claimed design.
